CIRCUIT ARRANGEMENT IN TELEVISION RECEIVERS

Robert Andrieu, Berlin, Germany, assignor to Telefunken Gesellschaft für Drahtlose Telegraphie m. b. H., Berlin, Germany, a corporation of Germany

Application February 15, 1937, Serial No. 125,715
In Germany February 20, 1936

6 Claims. (Cl. 178—7.3)

The invention concerns a circuit arrangement for control of saw-tooth generators in television receivers. It is here assumed that the generators require a negative potential impulse at their input tube for the production of the short arm of the saw-tooth curve and further that the detector circuit is connected in series in the manner that during the synchronizing impulse a negative potential exists with respect to cathode at control 5 grid of input tube.

In accordance with the invention the detector circuit is in this case directly connected with the control grid of input tube through a resistance.

The invention may be used in principle for all 10 conditions sufficing above assumptions.

Two embodiments of invention will be explained in what follows with the aid of the drawing.

In Figure 1 is represented the course of the 15 low frequency for the case that a carrier wave of a certain finite value S is increased by image currents and decreased by synchronizing impulses below this value S down to zero. Value S may thereby correspond to the black image points so 20 that the image points of maximum brightness are also reproduced by a carrier wave amplitude of maximum size. But, on the other hand, to value S may also be coordinated the image points of maximum brightness, in which case the maximum carrier wave amplitudes correspond accordingly to the black image points. The range of 25 the carrier wave amplitude below size S is in both cases reserved for signal indication alone, for instance, by the synchronizing impulses.

A circuit arrangement suitable for a transmitting method according to Fig. 1 is illustrated 30 in Fig. 2.

10 designates the secondary of a transformer whose primary is joined to the high frequency 35 amplifier. The detector circuit consists of this secondary winding, a rectifier 11, as well as a resistance 12 with condenser connected in parallel thereto and it is grounded over a potential source 13. Point P of detector circuit is connected 40 through a resistance 14 with the control grid of input tube 15 of a saw-tooth generator. The cathode of tube 15 is grounded.

The circuit arrangement according to Fig. 2 45 operates in the manner that there appears a potential for values of the carrier wave amplitude and therewith for values of the potential appearing at resistance 12 below value S at point P, said potential being below that of the earth potential. The size of potential source 13 is dimensioned in 50 the manner that with that potential drop at re-

sistance 12 which corresponds to value S , point P is just impressed with earth potential. As a result thereof the synchronizing impulses which as understood produce according to Fig. 1 the potential drop zero at resistance 12, cause the appearance at the control grid of tube 15 of a negative potential with respect to cathode. But carrier wave amplitudes and therewith also amounts of the potential drop at resistance 12 which exceed value S raise point P to a positive potential with 5 respect to earth, but, on the other hand, there is produced by the grid current generated by positive potentials in point P a potential drop at resistance 14 with the result that the control grid potential does not rise through the image currents noticeably above value corresponding to 10 value S . The mode of operation of saw-tooth generator need not be explained again in this connection, since it is described in application Ser. No. 61,499, filed Jan. 30, 1936.

Fig. 3 has reference to a transmitting method 15 whereby a carrier wave amplitude is modulated by the image currents from zero to value G , the synchronizing signals being given by carrier wave amplitudes which are greater than that corresponding to value G .

A receiving arrangement in accordance with invention and suitable for this method of transmission is shown in Fig. 4.

Therein the symbols 10 to 12, 14, 15 and P have 20 the same meaning as in Fig. 2. But the detector circuit is grounded through a direct current potential source 16 of reversed polarity of that in Fig. 2 and the transmitting direction of detector 25 11 is reversed with respect to Fig. 2.

The circuit scheme according to Fig. 4 operates 30 in the manner that earth potential appears at a point P with a carrier wave amplitude of the size G , in other words, that the potential 16 is as large as value G . Hence, the synchronizing 35 signals of Fig. 3 produce at point P a negative potential with respect to cathode of tube 15. As to the rest and in particular with respect to the potential drop produced by grid current at resistance 14, the manner of operation coincides completely with that according to Fig. 2.

The arrangement proposed according to the 40 invention insures the production of negative impulses of sufficient size at control grid of tube 15. An amplification of these impulses may, 45 however, be accomplished in the manner that a feedback coil 17 is provided in the saw-tooth generator whose one end is grounded and whose other end is connected with the control grid of input tube through resistance 18.

What I claim is:

1. A synchronizing apparatus comprising a vacuum tube, having anode, cathode and control electrodes, means for storing electrical energy connected in a current carrying electrode-cathode path of said tube, means for feeding back to the control electrode of said tube a portion of said stored energy during its discharge, a rectifier, resistive means connected to said rectifier, a source of fixed bias potential electrically connected to resistive means whereby the control electrode of said tube is maintained at a predetermined bias potential, means for impressing potentials representative of the potential fall across said resistive means onto a control electrode of the vacuum tube, means for maintaining said tube normally conducting by impulses exceeding a predetermined amplitude, and means for blocking said tube when said impulses fall below a definite value whereby said vacuum tube stores energy in said energy storage means during periods of conduction, said energy being discharged during periods when the vacuum tube is blocked.
2. A synchronizing apparatus comprising a vacuum tube having anode, cathode and control electrodes, means for storing electrical energy connected in a current carrying electrode-cathode path of said tube, means for feeding back to the control electrode of said tube a portion of said stored energy during its discharge, a rectifier, resistive means connected to said rectifier, a source of fixed bias potential electrically connected to resistive means whereby the control electrode of said tube is maintained at a predetermined bias potential, means for impressing potentials representative of the potential fall across said resistive means onto a control electrode of the vacuum tube, means for maintaining said tube normally conducting by impulses exceeding a predetermined amplitude, means for maintaining said tube current substantially constant during periods of conduction, and means for blocking said tube when said impulses fall below a definite value whereby said vacuum tube stores

energy in said energy storage means during periods of conduction, said energy being discharged during periods when the vacuum tube is blocked.

3. A sawtooth wave generator comprising means for receiving signals from a source external to the generator, means for impressing said signals onto a first uni-directional conductor, means for developing a potential difference in accordance with the current flow in said uni-directional conductor, a thermionic vacuum tube having anode, cathode and at least one control electrode, inductive means connected in the anode-cathode circuit of said tube and adapted to store electro-magnetic energy from at least a portion of the anode current of said tube, a uni-directional conductor connected substantially in parallel with said inductive means, means for impressing the potential developed in accordance with the current flow through said first uni-directional conductor onto the control electrode-cathode circuit of said thermionic tube, and a source of fixed bias potential connected in the control electrode-cathode circuit of said thermionic tube whereby said tube remains conducting throughout a range of received signal amplitude values and is maintained blocked by signals without the conducting amplitude range.

4. Apparatus in accordance with claim 3, wherein said uni-directional conductors each comprises a diode.

5. Apparatus in accordance with claim 3, wherein there is provided in addition resistance means connected serially with the control electrode of said thermionic tube and the means for developing a potential in accordance with the current flow through the first uni-directional conductor.

6. Apparatus in accordance with claim 3, wherein said means for developing a potential in accordance with the current flow in the first uni-directional conductor comprises a resistance connected serially with said uni-directional conductor and having the current from said conductor passing therethrough.

ROBERT ANDRIEU.
